UNITED STATES PATENT OFFICE.

CARL ADOLF HARTUNG, OF BERLIN, GERMANY.

APPARATUS FOR GAS ANALYSIS.

No. 892,955.

Specification of Letters Patent.

Patented July 7, 1908.

Application filed August 30, 1905. Serial No. 276,420.

To all whom it may concern:

Be it known that I, CARL ADOLF HARTUNG, engineer, a subject of the King of Prussia, residing at Berlin, Germany, have invented

5 an Improvement in Apparatus for Gas Analysis, of which the following is a specification.

The improved apparatus for gas-analysis consists of a mechanically - driven pump 10 which draws the gaseous mixture to be analyzed from a current of gas conducted through a pipe or conduit and pumps it into a vessel which is filled with the corresponding absorbents. For the pump, only constructions are employed which at each stroke throw a substantially constant amount of gas, *e. g.* special hydraulic gas-pumps. The reduction (due to the absorption of some of its constituents) in this constant amount 20 of gas is determined at each stroke by suitable measuring vessels or registering devices arranged in combination with the absorption-vessel, whereby the result of an analysis is given. After the stroke of the pump is completed, and thus after the completion of 25 the analysis, the absorption-chamber is brought into free communication with the atmosphere by positively-actuated valve-gearing, so that the residual gas can escape.

30 Before the commencement of the compression-stroke of the pump, this opening in the absorption-chamber is automatically closed again in a similar manner. The apparatus, which is provided with a registering device, 35 works quite automatically.

While in the automatically-operating gas-analysis apparatus heretofore known, the gases to be examined are either drawn or forced by means of a gas supply-pipe and a 40 special device directly through the measuring- or receiving-vessel. In the improved system a feeble branch current is diverted from the current of gas to be examined and the pipe or conduit for this branch current is 45 so arranged that it extends directly through the apparatus or in the immediate neighborhood thereof. This branch current of the gas to be examined is tapped at the testing place and returns to the main current at a 50 suitable point. In this arrangement, it is in most cases possible to work with the natural pressure-gradient in the by-pass as well as in the main current of gas, so that no further propelling means are required for 55 transferring the gas to the place where it is examined. The pipe for the by-pass can

be of any desired size in cross-section, without thereby causing retardation in the supply of the gas and therewith in the indication of the processes to be disclosed by the analysis. 60

If it be considered what difficulties occur in permanently-working gas-analysis apparatus by clogging of the necessarily narrow piping, the extraordinary technical advance obtained will be clearly seen. In cases 65 where stress is laid on increasing the rapidity of the current of gas in the by-pass, this can be effected in the simplest manner by providing nozzles acting like ejectors. In the apparatus heretofore known, this would involve difficulties, since the current of gas therein is temporarily interrupted by automatically opening and closing alternately-used passages by slide-valves or by rising and falling liquid columns and thus not permit the use of such great differences of pressure. In the improved arrangement, however, the sample to be analyzed is drawn into the gas-pump from the by-pass through a valve or a liquid seal, which is permanently 70 covered with the liquid. Thus while the gases pass continuously through the by-pass by reason of the natural pressure-gradient or other cause, the pump of the apparatus intermittently draws a sample from 75 this by-pass and brings this to the gas-analysis apparatus. Thus by means of the pump, the gaseous mixture, after it has been brought by means of special apparatus to a definite amount remaining constant for each 80 stroke, is compressed into the vessel containing the absorbent. Since these absorbents generally consist of liquids, this arrangement permits the passage of the gas through the absorption-liquid, whereby an extremely 85 rapid and complete absorption is obtained. The residue of gas left behind collects above the liquid and by its pressure actuates suitably arranged registering mechanism. In the apparatus heretofore known, it is not 90 possible to allow the gases to bubble through the absorption-liquid, since the absorption-liquid is thereby forced out of the absorption-vessel by the gas flowing in and this motion of the absorbent is employed for 95 registering purposes. Further, the gases must go back again in the same manner as that in which they come, which also renders impossible the forcing thereof through 100 the liquid.

In order to remove the residue of gas over the absorbent after the completion of the

100

105

110

analysis, and to equalize the pressure in the registering mechanism again with the atmospheric, in the improved construction a valve or the like closing the space above the absorption-liquid opens automatically, which closing device is likewise automatically closed before the commencement of the analysis. In this manner, I entirely prevent the residue of gas left from one analysis 10 from mixing with the gaseous mixture of the next. In the apparatus heretofore known, the residue of gas in the receiving burette is forced or drawn back and then, after the gas-passages have been reversed by opening 15 the various valves or the like, is carried away by the freshly entering current of gas with which it naturally will mix. The method of operation, which is quite new technically, and also the advantages obtained 20 by the new arrangement can also be clearly seen here.

I will now proceed to give a detailed description of the apparatus and of the hereinabove clearly characterized system. I will 25 however definitely state that the form of construction in the accompanying drawings is only given by way of example.

In these drawings, *a*, *a* is the pipe through which the by-pass current of gas to be investigated is conducted. The pipe *a*, *a* is here placed as near as possible to the vessel forming a check or seal, which however is not absolutely necessary; *b*, *c*, *d*, *e*, *f*, *g* form the parts of a hydraulic gas-pump which is specially constructed by me for the present purpose. The driving and sealing liquid flows through *b* to *c*; *d* is the air-outlet-and air-inlet pipe; *e* an intermittently-working siphon; *f* the connecting pipe leading to the cylinder *g* of the gas-pump. A similar gas-pump with intermittently-working siphon has already been constructed by Bonny, yet this combines the water-supply vessel *c* with the cylinder *g* of the pump-chamber, into which it allows the siphon *e* to open. This construction is not however usable for gas-analysis-purposes and for carrying out separate analyses, since it is not possible to prevent the gases from being contaminated with foreign matter. In the first place, the supply of sealing liquid in practice will never be so controlled that it does not carry with it any foreign gases, which are cut off during the rising of the liquid and contaminate the gaseous mixture in the pump-cylinder. In the second case, it is not permissible to allow the end of the siphon, as Bonny does, to dip into liquid, since this interferes with complete emptying thereof. This is however absolutely necessary in a siphon in order to obtain a constant height of liquid. If, however, the lower end of the siphon opens into the atmosphere, this on breakage of the column of liquid in the siphon causes air to flow 65 into the pump-cylinder which is under a re-

duced pressure, under which conditions any exact work in gas-analysis would obviously be impossible. By the separation of the cylinder *g* from the collecting vessel *c*, the transfer of the liquid-supply-pipe *b* and of the siphon *e* to this collecting chamber or vessel *c* and the connection of this vessel so that it always remains closed by a residue of liquid, I have obviated these disadvantages and this hydraulic gas-pump is rendered useful 75 for the purposes of gas-analysis.

h shows a liquid seal through which the gas to be analyzed is drawn from the pipe *i* branching from the pipe *a*. The pipe *i* in the present case has been made as short as possible, 80 in order to obtain always fresh gas directly through *a*. In order to render this possible, mercury is used as the sealing liquid in *h*, whereby a very compact construction of *h* is simultaneously rendered possible. The connection of the pump with the absorption-vessel *l* is made through *k*, the pipe dipping into the liquid contained in the said vessel. A rising and overflow of the liquid in the pipe *k* is prevented by arranging a valve therein 85 or by making *k* of sufficient height. A pipe *m* extends into the pump-cylinder *g*, which pipe forms a hydraulic trap with the sealing vessel *n*, this trap allowing gas to pass out until the lower end of the pipe *m* is covered 95 with liquid, but preventing the entrance of atmospheric air when there is a vacuum in *g*. To the absorption-vessel *l* are connected the pipes *o* and *p*; *o* is bent to a U-shape one limb of the U extending into the pipe *q* which again communicates through the connecting piece *r* with the vessel *c* of the hydraulic gas-pump. To *p* is connected a registering device *s*.

The apparatus itself works in the following manner:—When water runs in through *b*, *c* gradually fills together with the communicating pipes and vessels *d*, *e*, *g*, *q*. From the cylinder *g*, the gaseous mixture present is driven first through *m* and the hydraulic check-valve *n* into the atmosphere, since only a very small head of liquid has to be overcome in *n*. As soon as the liquid in *g* covers the pipe *m*, the further contents must be forced through the pipe *k* and through the absorbent liquid in the absorption-vessel *l*. The pipe *o* has been previously closed by the sealing liquid rising in *q* which is open at its upper end. By reason of the device *m*, *n*, at each stroke, the same quantity of the gaseous mixture in *g* is pumped to *l*. From the excess pressure (above the atmospheric) in *l*, a deduction can consequently be drawn as to the fraction of the gaseous mixture which has been resorbed. The registering device *s* 120 serves for indicating and determining the result. As soon as the siphon *e* begins to work at the highest position of the liquid, the vessels *c*, *g* and *q* empty. A vacuum is produced in *g* and a fresh amount of gas is drawn 125 130

out of the tube *a* through *h* and *i*. In *g*, the sealing liquid frees the pipe *o* and the residue of gas under a pressure above the atmospheric escapes through the said pipe from *l*, in which vessel the atmospheric pressure again reigns. After breakage of the column of liquid in the siphon *e*, the process is repeated in the manner above described.

I claim as my invention

- 10 1. An automatic apparatus for gas-analysis, comprising the combination of a gas-pump adapted to work intermittently and automatically to suck the gaseous mixture to be analyzed from a pipe through which a 15 constantly circulating gas current is conducted, with vessels containing absorbents and combined with measuring or registering devices, in which vessels the gaseous mixture to be analyzed is forced through the absorbents, and with a device allowing the residue of gas after the analysis to escape automatically without being able to reenter the gas-pump.
- 20 2. An automatic apparatus for gas-analysis, comprising the combination of a gas-pump adapted to work intermittently and automatically to suck the gaseous mixture to be analyzed from a pipe, through which a constantly circulating gas current is conducted, with vessels containing absorbents through which the gaseous mixture is to be forced, said main pipe having a short branch and a seal into which said branch enters.

3. An automatic apparatus for gas-analysis, comprising the combination of a gas-pump adapted to work intermittently and automatically to suck the gaseous mixture to be analyzed from a pipe, through which a constantly circulating gas current is conducted, with vessels containing absorbents, 40 through which the gaseous mixture is to be forced, and with a collecting vessel separate from the cylinder of the collecting pump, and a water supply and intermittently working siphon opening into the collecting vessel so 45 that action of the driving water upon the gases is avoided.

4. An automatic apparatus for gas-analysis, comprising the combination of a gas pump adapted to work intermittently and automatically to suck the gaseous mixture to be analyzed from a pipe, through which a constantly circulating gas current is conducted, with vessels containing absorbents through which the gaseous mixture is to be forced and 55 a hydraulic check valve with which the cylinder of the pump is connected and through which a part of the gas may escape, whereby the final amounts of gas pumped are always equal.

Signed by me this 17th day of August 1905.
